(57) **CLAIM**

The ornamental design for a Christmas decoration, as shown and described.

DESCRIPTION

FIG. 1 is a perspective view of a Christmas decoration showing my new design;

FIG. 2 is a front elevational view thereof;

FIG. 3 is a side elevational view thereof, as seen from the left side relative to FIG. 1;

FIG. 4 is a rear elevational view thereof;

FIG. 5 is a top view thereof; and,

FIG. 6 is a bottom view thereof.

The broken lines are for illustrative purposes only and form no part of the claimed design.
